UNITED STATES PATENT OFFICE.

FOUNTAIN S. BRAID, OF NEW YORK, N. Y.

ELEVATOR-CONTROLLER.

SPECIFICATION forming part of Letters Patent No. 605,471, dated June 14, 1898.

Application filed January 25, 1898. Serial No. 667,847. (No model.)

To all whom it may concern:

Be it known that I, FOUNTAIN S. BRAID, a citizen of the United States, residing in New York, (Brooklyn,) in the State of New York, have invented a certain new and useful Improvement in Elevator-Controllers, of which the following is a specification.

The invention relates to that class of improvements in elevators in which the act of opening the shaft-door clamps the hand-rope through a train of mechanism and prevents operating the hoisting mechanism until the door is again closed and the hand-rope released.

15 The object of this invention is to simplify the mechanism, while affording a reliable, positive, and uniform grip on the rope, independent of the force exerted in opening the door.

20 It consists, essentially, of a clamp carried on the car and inclosing the rope between its jaws, actuated by the movement of a piston in a cylinder also carried on the car and receiving pressure from a reservoir which may 25 be at a distant point connected to the cylinder through a flexible tube or hose, and means for admitting the pressure to the cylinder by the act of opening the shaft-door. I prefer to use compressed air admitted to and exhausted from the cylinder through a suitable 30 valve, requiring but little force to operate it and consequently offering but little resistance to the motion of the shaft-door, while the force exerted upon the rope by the clamp is 35 entirely independent of such movement and is wholly determined by the pressure received in the cylinder. The force is practically uniform and may be regulated by increasing or diminishing the normal pressure in the reservoir.

40 The accompanying drawings form a part of this specification and show the manner in which I have carried out the invention.

Figure 1 is a front elevation of a car 45 equipped in accordance with my invention. Certain portions are omitted for clearness. The elevator-shaft is shown in vertical section. The remaining figures are on a larger scale. Fig. 2 is a plan or top view of the car and a horizontal section through the shaft. Fig. 3 is a corresponding vertical section of a portion of the shaft, showing the top of the

door and its connections in elevation. Fig. 4 is a front elevation of the upper portion of the car and its mechanism. Figs. 5 and 6 are 55 sectional views showing certain details of construction.

Similar letters of reference indicate the same parts in all the figures.

A is a passenger-elevator of any ordinary 60 or approved construction, guided vertically in the shaft B by the ways B' and raised and lowered by any suitable hoisting ropes and mechanism (not shown) controlled by the hand-rope A', passing through the car, as 65 usual.

B² is the shaft-door, sliding horizontally at the landing in ways. (Not shown.) The arrangement at each landing is similar and a description of one will suffice.

70 On the top of the car is mounted the cylinder C, receiving compressed air behind the piston D through a pipe C', a portion of which is a flexible tube C², from a reservoir C³, located at any convenient place, preferably at 75 the bottom of the shaft adjacent to the hoisting mechanism, and supplied by an air-pump C⁴, of any approved type, operated either directly or from a moving part of the hoisting mechanism. From the front of the piston D 80 extends a rod D', suitably guided and carrying at its end a block D², having a vertical semicylindrical groove d and forming with the fixed block D³, having a similar groove, a pair of clamping-jaws partly inclosing the 85 hand-rope A'. The movable jaw D² slides in the ways D⁴, carrying the fixed jaw D³ and firmly secured to the top of the car. A spring D⁵ within the cylinder exerts its force in the direction to move the piston backward and 90 hold the jaws normally open.

E is a three-way cock placed in the pipe C' at any convenient point adjacent to the cylinder. The plug E¹ is turned by the arm E² from the horizontally-vibrating lever E⁴ 95 through the link E³. The ports are so arranged (see Fig. 6) that a quarter-turn of the plug admits air-pressure behind the piston and the reverse movement shuts off the supply and allows the compressed air in the cylinder to escape through the opening e. The lever E⁴ turns on a fixed center E⁵ and is subject to the force of a spring E⁶, tending to move it in the direction to exhaust the

cylinder, such motion being limited by the fixed stop A². On the overhung end of the lever is a vertical face-plate E⁷, by which the lever is moved in opposition to its spring 5 through means to be now described.

On the upper portion of the framing carrying the door B² and within the shaft is mounted a lever F, the lower arm carrying a roller F' and the upper arm joined to one end of a link 10 F², connected at the other to a projecting lug G² on a cam device serving to change the motion angularly, so that it acts against the plate E⁷, above described. This device consists of a cylindrical casing divided on a spiral line, one portion, G, fixed to the framing and the other, G', carrying the lug G², rotatable relatively thereto by the motion of the link F². Through the axis extends a rod H, the outer end of which carries a roller H', 15 lying in the path of the plate E⁷, and the other squared to match to a similarly-shaped extension G³ of the fixed portion G, in which it may slide, but is held against rotation. The movable portion G' rests against the 20 shoulder h on the rod and when partially rotated travels up the spiral, thus forcing the rod and its roller H' outwardly, or, rather, inwardly relatively to the shaft. This rotative motion is transmitted from the lever F and is 25 received by the latter from the movement of the door B² in the direction to open it. The door carries along its top edge a track or way B³, curved downwardly at B⁴ adjacent to the roller F' and lying in such relation thereto 30 that as the door is moved in the direction to open it the curve B⁴ strikes the roller and begins to turn the lever F, the turning continuing until the roller lies upon the horizontal portion B³ of the track and travels idly thereon 35 40 as the door is moved farther without causing further movement of the lever. When the car is stopped with its floor approximately level with the landing, the plate E⁷ lies adjacent to and in the line of motion of the rod H, and as the latter is thrust outward from 45 its casing by the act of opening the door its roller strikes the plate and turns the lever E⁴, which through the link E³ and arm E² communicates the motion to the plug E', as above 50 described, and admits pressure behind the piston and closes the clamp. The parts are so proportioned that a full quarter-turn is given to the plug and the full pressure is immediately felt by the jaws D² D³ and hand-rope A'. While thus held, the rope cannot 55 be moved relatively to the car, and consequently the latter cannot be started in either direction. On closing the door the parts assume their normal positions, reversing the

60 plug E' and allowing the air behind the piston D to escape. The piston is immediately forced backward by the spring D⁵, carrying with it the jaw D², and thus the rope is again liberated, allowing the operator through its medium to start the hoisting mechanism. 65

The plate E⁷ is given considerable vertical length, so that the roller H' will be sure to find it even though the car-floor and landing be not exactly in the same plane. The upper and lower portions of the plate are curved 70 backward, as shown, and serve to strike the roller and actuate the clamp if by accident or design one of the shaft-doors should be opened from its landing and not closed before the passage of the car. 75

The flexible portion C² of the pipe C' allows the free travel of the car without interrupting the communication with the reservoir C³. The latter may be equipped with a safety-valve loaded to a predetermined pressure, 80 which will lift when that pressure is exceeded and thus tend to maintain a constant pressure while the pump is running. 85

Modifications may be made without departing from the principle of the invention or sacrificing its advantages. 90

The train of mechanism from the door to the cylinder may be varied within wide limits or other means substituted, and other means for controlling the admission and exhaust 95 cock may be employed in place of the three-way cock shown.

Although I have described the invention as using air-pressure, it will be understood that other gases or fluids under pressure will serve 95 successfully.

I claim—

In an elevator-controller of the character herein set forth, a clamp carried by the car and adapted to grasp and hold the operating-rope, a cylinder also carried by the car and receiving pressure, a piston mounted in said cylinder and moved by said pressure to actuate said clamp, and mechanism operated by the door in opening and closing, controlling 100 the admission of pressure to said cylinder, so that the operating-rope will be clamped when said door is open and released when closed, all combined and arranged to serve substantially as and for the purposes herein 105 specified.

In testimony that I claim the invention above set forth I affix my signature in presence of two witnesses.

FOUNTAIN S. BRAID.
